UNITED STATES PATENT OFFICE.

ROBERT P. FRIST, OF LONG BEACH, CALIFORNIA, ASSIGNOR OF ONE-HALF TO ARCHIE C. FRIST, OF LONG BEACH, CALIFORNIA.

FRUIT STEMMER AND CLEANER.

Application filed April 20, 1926. Serial No. 103,232.

This invention relates to an improved device for removing the stems from and cleaning deciduous fruits and the like, and is particularly an improvement over the device 5 disclosed in my prior Patent No. 1,403,399, issued January 10, 1922.

An object of this invention is to provide an improved device for cleaning and removing the stems of fruit, wherein there is a passageway in which is arranged a plurality of impingement elements, and to provide means for rotating these elements relatively to each other.

Another object of this invention is to provide an improved machine having the above mentioned characteristics in which there is an entrance through which the fruit may be fed to the machine, and to provide a construction in the entrance for breaking up 20 the clusters of fruit.

A further object of this invention is to combine with a machine of the character disclosed in my prior patent a construction for separating the fruit according to their 25 respective sizes.

With the foregoing and other objects in view which will be made manifest in the following detailed description and specifically pointed out in the appended claims, reference is had to the accompanying drawings 30 for an illustrative embodiment of the invention, wherein:

Figure 1 is a top plan view of the improved machine,

Fig. 2 is a side elevation of the same,

Fig. 3 is a view in end elevation taken substantially in the direction of the arrow 3 upon Fig. 2,

Fig. 4 is a vertical section taken upon the 40 line 4—4 of Fig. 1, and

Fig. 5 is a vertical section taken on the line 5—5 of Fig. 2.

Referring to the accompanying drawings 45 wherein similar reference characters designate similar parts throughout, the improved machine will be described in connection with handling raisins, as it is primarily designed to be used for this purpose, although it will be readily understood that the machine may be equally well employed when using various other kinds of fruit. The device consists of a barrel 10 supported on any suitable support 11. The rear end of the barrel consists of a plurality of stationary aligned 50 segments 12 which are spaced from each

other and which are stationarily mounted on the support 11. In the forward end of the barrel there is a wall 14 having a plurality of apertures 15 therein. These apertures are normally closed by removable plugs 16 forming removable closures. An air pipe 17 is connected to the front wall 14 and serves to convey compressed air to the interior of the barrel so as to discharge a stream of air rearwardly through the barrel. The stationary 60 segments 12 are provided with recessed side faces forming annular flanges 18, and impingement elements are disposed therebetween. These impingement elements are in the form of rings 19 having annular shoulders 20 on their side faces which fit within and bear against the annular flanges 18. The impingement elements may be of any desired construction, but the preferred form is to employ strips of sheet metal 21 arranged in a parallel manner within the rings 19 and which have their forward edges provided with tongues bent alternately in opposite directions, such as is clearly disclosed in my prior patent. 70

Shafts 22 and 23 are arranged upon opposite sides of the barrel and are rotatable within bearings 24 and 25 respectively, which can be provided on the stationary segments 12. These shafts carry pinions 26 and 27 respectively, which mesh with gear teeth formed on the exterior surfaces of the rings 19. The pinions 26 mesh with the gear teeth on alternating impingement elements and the pinions 27 mesh with the gear teeth on the intermediate impingement elements. As a means for rotating the shafts, standards 28 are provided on one side of the barrel and these standards provide bearings for two short shafts 29 and 30. On the upper 80 shaft 29 there is a pulley 31 adapted to be driven by a belt 32 from any suitable source of power, and also a pinion 33 which meshes with a gear 34 mounted on the lower short shaft 30. The pinion 34 meshes with the pinion 26 on the shaft 22. From this construction 85 it will be appreciated that when the pulley 31 is rotated, the gear 34 will be driven, rotating one of the impingement elements. This particular impingement element also 90 meshes with a pinion on the shaft 23, so that 95

100

105

110

the shaft 23 is rotated by the gear 34 through the impingement element with which it meshes. The pinion 35 and the pinion on the shaft 32 with which it meshes cause the shaft 22 to be rotated in a direction opposite to the direction of rotation of the shaft 23. Consequently, alternate impingement elements will be rotated in one direction and intermediate impingement elements 10 will be rotated in an opposite direction.

Between the forward wall 14 and the foremost impingement element there is provided an entrance indicated at 36, through which the fruit may be supplied to the barrel. 15 This entrance has provided thereon a plurality of stationary segments 37 similar to the stationary segments 12, and has rotatably mounted between these stationary segments cluster breaking elements 38. The stationary segments 37 and the cluster breaking elements 38 are very similar in construction to the stationary segments 12 and the impingement elements 19, except that these parts are provided with a plurality of parallel bars or rods, whereas the segments 12 and the impingement elements 19 are preferably provided with strips of sheet metal having their forward edges provided with alternately bent lugs or tongues. Vertical 20 shafts 39 and 40 are rotatably mounted in bearings on the sides of the stationary segments 37, and these shafts are driven through minor gears by their respective horizontal shafts 22 and 23. They carry 25 pinions meshing with the gear teeth formed on the exterior surfaces of the cluster breaking elements 38, so that some of the cluster breaking elements will be rotated in one direction while other cluster breaking elements 30 will be rotated in another direction. The fruit can be fed into this entrance so provided by means of a hopper 41. At the rear of the barrel there are arranged two outlets, indicated at 42 and 43, and a plurality of 35 parallel bars or rods 44 are arranged in the barrel between these outlets, forming a type of coarse screen. A finer screen 45 is mounted over the rear end of the barrel behind the outlet 43.

40 The operation of the device is as follows: The compressed air is supplied to the barrel by means of the air pipe 17 and is forced therethrough between the strips 21 of the impingement elements, passing through the screens 44 and 45 on leaving the barrel. The 45 raisins or other fruit are supplied to the barrel by means of the hopper 41 and the pulley 31 is continually driven by the belt 32. From the driving connection above explained, the cluster breaking elements 38 are rotated relatively to each other and in opposite directions, so that if the raisins are in clusters, they will be effectively broken up and separated from each other by the 50 relative rotation of the cluster breaking ele-

ments. The separated raisins or other fruit then fall into the barrel and are blown rearwardly by the air blast striking against the strips or plates 21 of the impingement elements. Because of the construction of the plates or strips 21 of the impingement elements, the stems on the raisins will be effectively caught and separated from the fruit. As the various impingement elements are rotating relatively to each other and in opposite directions, the positions of the plates or strips 21 are continually varied, so that each raisin on passing through the barrel will encounter several plates on various impingement elements, insuring that the stems will be removed. Because of the raisins striking against several impingement elements, any dirt or undesirable foreign matter which may be on the exterior of the raisins will be effectively removed therefrom and the stems and the dirt will be blown rearwardly through the screens 44 and 45. The raisins, however, will strike the screens 44 and 45, the larger raisins being stopped by the screen 44 and caused to fall, passing from the barrel through the outlet 42. The smaller raisins, however, will pass through the screen 44 and will be stopped by the finer screen 45, passing from the barrel through the outlet 43. From this construction it will be appreciated that raisins or similar fruit can be thrown into the hopper 41, and on coming out of the machine, they will have their stems removed and be thoroughly cleaned, and also they will be separated according to their sizes.

The purpose of the plugs 16 is as follows: It sometimes happens that the raisins on falling into the barrel through the entrance 36 will not be picked up by the air blast, but will fall to the bottom of the barrel immediately behind the front wall 14. When many of these raisins accumulate in this position, the lower plugs 16 can be removed, and as there will be a partial vacuum formed in the barrel immediately behind the front wall because of the discharge of air, air from the outside of the barrel will be drawn through the apertures 15, thus causing a material increase in air flow, sweeping up the raisins which may have accumulated on the bottom of the barrel and forcing them rearwardly through the impingement elements.

From the above described construction it will be appreciated that the improved machine for handling fruits is a decided improvement over the construction disclosed in my prior patent, the important feature being that in this construction there is provided means for rotating or moving the various impingement elements relatively to each other. Furthermore, there is provided a mechanism for breaking up the clusters of raisins on entering the machine, so that

the operation of the impingement elements will become much more effective.

It will be understood that various changes may be made in the detail of construction 5 without departing from the spirit or scope of the invention as defined by the appended claims.

I claim:

1. A device of the class described comprising means providing a passageway, fluid means for forcing fruit through the passageway, impingement elements arranged in the passageway, and means for moving said impingement elements.

2. A device of the class described comprising means providing a passageway, fluid means for forcing fruit through the passageway, impingement elements arranged in the passageway, and means for moving some of 20 said impingement elements relatively to the others.

3. A device of the class described comprising means providing a passageway, fluid means for forcing fruit through the passageway, impingement elements arranged in the passageway, and means for rotating said impingement elements.

4. A device of the class described comprising means providing a passageway, fluid means for forcing fruit through the passageway, impingement elements arranged in the passageway, and means for rotating some of 30 said impingement elements relatively to the others.

5. A device of the class described comprising means providing a passageway, fluid means for forcing fruit through the passageway, impingement elements arranged in the passageway, means for rotating some of said 40 impingement elements in one direction, and means for rotating the others in an opposite direction.

6. A device of the class described comprising a barrel, impingement elements rotatably mounted in said barrel, one behind the other, means for forcing fruit through the barrel and impingement elements, shafts rotatably mounted upon said barrel, one shaft being gearedly connected to some of said 50 impingement elements and the other shaft being gearedly connected to the other impingement elements, and means for rotating said shafts in opposite directions.

7. A device of the class described comprising means providing a passageway, impingement elements arranged in said passageway, fluid means for forcing fruit through the passageway, there being an entrance to the passageway for the fruit forwardly of the impingement elements, and means disposed 60 in said entrance for breaking up clusters of fruit.

8. A device of the class described comprising means providing a passageway, impingement elements arranged in said passageway,

fluid means for forcing fruit through the passageway, there being an entrance to the passageway for the fruit forwardly of the impingement elements, and means disposed in said entrance for breaking up clusters of 70 fruit comprising rotatable elements having passages therethrough rotatably mounted in the entrance and means for rotating one of said elements relatively to the other.

9. A device of the class described comprising means providing a passageway, impingement elements arranged in said passageway, fluid means for forcing fruit through the passageway, there being an entrance to the 75 passageway for the fruit forwardly of the impingement elements, and means disposed in said entrance for breaking up clusters of fruit comprising rotatable elements having passages therethrough rotatably mounted in the entrance and means for rotating said elements in opposite directions.

10. A device of the class described comprising means providing a passageway, impingement elements arranged in said passageway, fluid means for forcing fruit 80 through the passageway, there being an entrance to the passageway for the fruit forwardly of the impingement elements, and means disposed in said entrance for breaking up clusters of fruit comprising elements 85 mounted in said entrance having passages therethrough and means for moving said elements relatively to each other.

11. A device of the class described comprising means providing a passageway, pneumatic means for forcing fruit through the passageway, means providing coarse and fine screens in the passageway behind the impingement elements, the coarse screen being arranged forwardly of the fine screen, and means providing outlets from the passageway forwardly of each screen.

12. A device of the class described comprising means providing a passageway, an air pipe leading to the forward end of the 110 passageway for discharging an air blast therein, impingement elements arranged in the passageway, means providing an entrance for the front to the passageway between the air pipe and the impingement elements, an apertured wall closing the forward end of the passageway about the air pipe, and removable closures for the apertures therein as and for the purpose described.

13. A device of the class described comprising a barrel having its forward end closed and having its rearward end formed of stationary spaced sections, an air pipe leading into the forward end of said barrel, impingement elements rotatably mounted between the sections of the barrel, a screen closing the rear end of the barrel, two shafts 125 rotatably mounted upon the barrel, one shaft being gearedly connected to alternate impingement elements, means for rotating said 130

shafts in opposite directions, and means providing an entrance for fruit to the barrel forwardly of the foremost impingement element.

5 14. A device of the class described comprising a barrel having its forward end closed and having its rearward end formed of stationary spaced sections, an air pipe leading into the forward end of said barrel, 10 impingement elements rotatably mounted between the sections of the barrel, a screen closing the rear end of the barrel, two shafts rotatably mounted upon the barrel, one shaft being gearedly connected to alternate impingement elements, means for rotating said shafts in opposite directions, means providing an entrance for fruit to the barrel forwardly of the foremost impingement element, cluster breaking elements having passages therethrough rotatable in the entrance, 15 and means for rotating said cluster breaking elements relatively to each other.

15. A device of the class described comprising means providing a passageway, 20 pneumatic means for forcing fruit through the passageway, there being a series of impingement elements arranged one behind the other in the passageway, means for feeding fruit to the passageway forwardly of the 25 impingement elements so as to be blown therethrough, means for segregating the fruit from other material after passing through the impingement elements, and means for rotating some of the impingement 30 elements relatively to others, said impingement elements being in the form of annular rings having a plurality of sheet metal blades extending thereacross.

40 16. A device of the class described comprising means providing a passageway, pneumatic means for forcing fruit through the passageway, there being a series of impingement elements arranged one behind the other in the passageway, means for feeding fruit to the passageway forwardly of the impingement 45 elements so as to be blown therethrough, means for segregating the fruit from other material after passing through the impingement elements, and means for rotating some 50 of the impingement elements relatively to others, said impingement elements being in the form of annular rings having a plurality of parallel blades extending thereacross and at planes parallel to the direction of flow 55 through the passageway.

60 17. A device of the class described comprising means providing a passageway, pneumatic means for forcing fruit through the passageway, there being a series of impingement elements arranged one behind the other in the passageway, means for feeding fruit to the passageway forwardly of the impingement elements so as to be blown therethrough, 65 means for segregating the fruit from other material after passing through the impinge-

ment elements, and means for rotating some of the impingement elements relatively to others, said impingement elements being in the form of annular rings having a plurality of parallel blades extending thereacross and at planes parallel to the direction of flow through the passageway, the forward edges of the blades being notched. 70

75 18. A device of the class described comprising means providing a passageway, pneumatic means for forcing fruit through the passageway, there being a series of impingement elements arranged one behind the other in the passageway, means for feeding fruit to the passageway forwardly of the impingement elements so as to be blown therethrough, means for segregating the fruit from other material after passing through the impingement elements, and means for rotating some of the impingement elements relatively to others, said impingement elements being in the form of annular rings having a plurality of parallel blades extending thereacross and at planes parallel to the direction of flow through the 80 passageway, the forward edges of the blades having notches which are formed by forming lugs on the blades and bending alternate lugs laterally in one direction and bending the intermediate lugs laterally in the 85 other direction.

90 19. A device of the class described comprising means providing a passageway, pneumatic means for forcing fruit through the passageway, there being a series of impingement elements arranged one behind the other in the passageway, alternate impingement elements being stationary and intermediate impingement elements being 95 movable, means for rotating alternate movable impingement elements in one direction, means for rotating intermediate movable impingement elements in the opposite direction, means for feeding fruit to the passageway forwardly of the impingement elements, and means for segregating the fruit from other material after having passed 100 through the impingement elements.

105 20. A device of the class described comprising means providing a passageway, impingement elements disposed in the passageway, pneumatic means for forcing fruit through the passageway and impingement elements, means for moving some of the impingement elements relatively to the others, there being an entrance to the passageway through which fruit may be fed therethrough, cluster breaking elements having 110 passages therethrough disposed in the entrance to the passageway, means for moving said cluster breaking elements relatively to each other, said cluster breaking elements being operatively connected to the impingement elements so as to be driven thereby, and means for segregating fruit 115 120 125 130

from other material after passing through the impingement elements.

21. A device of the class described comprising means providing a passageway, rotatable impingement elements disposed in the passageway, shafts located on opposite sides of the passageway and gearedly connected to the impingement elements, one shaft being gearedly connected to alternate impingement elements and the other shaft being gearedly connected to intermediate impingement elements, stationary impingement elements disposed between the mentioned impingement elements, there being an entrance to the passageway forwardly of the impingement elements through which

fruit may be fed, cluster breaking elements rotatably mounted in said entrance, one cluster breaking element being gearedly connected to one shaft so as to be rotated thereby, the other cluster breaking element being gearedly connected to the other shaft so as to be rotated thereby, means for rotating said shafts in opposite directions, pneumatic means for forcing the fruit through the passageway and impingement elements, and means for segregating the fruit from other material after passing through the impingement elements. 20 25

In testimony whereof I have signed my name to this specification. 30

ROBERT P. FRIST.
